United States Patent Office

Des. 208,820
Patented Oct. 3, 1967

208,820

ELECTRONIC ORGAN

Charles A. Ross, 7th and S. Steuben,
Chanute, Kans. 66720

Filed Aug. 22, 1966, Ser. No. 3,560

Term of patent 14 years

(Cl. D56--2)

Fig. 1.

Fig. 2.

FIG. 1 is a rear, top perspective view of an electronic organ showing my new design;

FIG. 2 is a front, top perspective view of an electronic organ showing my new design.

The bottom is plain.

The dominant features of my design reside in the parts shown in solid lines.

The grill fragmentarily shown is continuous within the boundaries indicated.

I claim:

The ornamental design for electronic organ, substantially as shown and described.
